UNITED STATES PATENT OFFICE.

THOMAS ANDREW OLIVER, OF BRAMCOTE, ENGLAND.

DESIGN FOR A LACE-PATTERN.

SPECIFICATION forming part of Design No. 25,379, dated April 14, 1896.

Application filed March 2, 1896. Serial No. 581,589. Term of patent 3½ years. Registered in England July 4, 1894, No. 257,429.

To all whom it may concern:

Be it known that I, THOMAS ANDREW OLIVER, a subject of the Queen of Great Britain and Ireland, and a resident of Southfield 5 House, Bramcote, in the county of Nottingham, England, have invented and produced a new and original Design for a Lace-Pattern, (for which I have obtained a design patent in England, No. 257,429, dated July 4, 1894,) of 10 which the following is a specification, reference being had to the accompanying drawings, in which—

Figure 1 shows a part of the lace-pattern. Fig. 2 is a section on line 2 2, Fig. 1.

15 The leading feature of my design consists of a series of a lace-pattern having fern-leaves *a* and sprays *b* on a net or ground

of open-work *c*, every leaf having its leaf-stalk *d* raised above the blade thereof. The said leaves are disposed solely along the edge 20 of the fabric and form a scalloped border, while the sprays are arranged within and near said scalloped border of leaves.

What I claim is—

The design for a lace-pattern substantially 25 as herein shown and described.

In testimony that I claim the foregoing as my invention I have signed my name, in presence of two witnesses, this 4th day of January, 1896.

THOMAS ANDREW OLIVER.
